(57) **CLAIM**

The ornamental design for a folding desk, as shown and described.

DESCRIPTION

FIG. 1 is a front perspective view of the desk;

FIG. 2 is a rear perspective top view of the desk;

FIG. 3 is a top plan view of the desk;

FIG. 4 is a bottom plan view of the desk;

FIG. 5 is a front elevational view of the desk;

FIG. 6 is a rear elevational view of the desk;

FIG. 7 is a left side elevational view of the desk;

FIG. 8 is a left side elevational view of the desk in a folded position; and,

FIG. 9 is a rear perspective top view of the desk in a folded position.

The broken lines in the drawings show environmental structure that form no part of the design to be patented.

The right side elevational view of the desk is a mirror image of the left side elevational view of the desk.
